CLAIM

The ornamental design for an electric spin scrubber, as shown and described.

DESCRIPTION

FIG. 1 is a front view of the electric spin scrubber;

FIG. 2 is a back view thereof;

FIG. 3 is a left side view thereof;

FIG. 4 is a right side view thereof;

FIG. 5 is a top view thereof;

FIG. 6 is a bottom view thereof;

FIG. 7 is a perspective view thereof;

FIG. 8 is another perspective view thereof; and,

FIG. 9 is an enlarged view taken from FIG. 7.

The broken lines illustrate environment and form no part of the claimed design.

(Continued)

The dash-dot lines illustrate the boundary of the enlarged view and form no part of the claimed design.

1 Claim, 9 Drawing Sheets
